VEST

Leo Fruhauf, Pelham, N. Y.

Application September 13, 1934, Serial No. 743,891

5 Claims. (Cl. 2—102)

My present invention relates to clothing, and resides particularly in the provision of means for and a method of effecting elimination of usual wrinkles in men's coats below the collar, and for improving the fit of the collar on or at the back of the neck.

In the majority of cases where ready-made coats are worn, and often even in the case of made-to-order coats, there appears below the collar and between the shoulders of the wearer, a wrinkle which no amount of alteration or fitting will eliminate. It has been proposed to insert a pad in the coat below the collar and between the shoulders to fill out the coat at the area where the wrinkle usually occurs. However, there are serious objections to the attachment of pads to the coats, which reside chiefly in the facts that while the wrinkles may, in some cases, be eliminated by the pads, the outlines of the pads are noticeable when the coats are worn. Also, when coats with pads attached thereto are pressed, a shine is imparted to the outer surface of the coat along the edges of the pads. Furthermore, when the coats are removed the pads are visible.

Aside from the foregoing objections to the provision of a pad in or on the coat itself for the purpose of eliminating wrinkles, attaching the pad to the coat fails to take into consideration the importance of "building up the body" so that the coat will conform to the surface therebeneath. That is, there is a hollow between the shoulders and below the necks of most men, and when the pad is attached to the coat itself the pad merely lies within the hollow and moves with the coat. Furthermore, in the case of round-shouldered people, it is usually the case that the coat collar does not snugly fit the neck, and even with the pad attached in the coat this condition still exists.

With the foregoing in mind, the principal general object of my present invention is to eliminate the wrinkling at the backs of coats below the collar by "building up the body" by providing means preferably on or in the vest to fill out the hollow at the area below the neck and between the shoulders, and without creating a noticeable bulge or uneven surface.

The means for accomplishing the foregoing objects are shown in several preferred illustrative forms in the accompanying drawing, wherein

Fig. 1 is a side elevation of a vest showing in dotted lines a pad attached thereto in accordance with one form of my invention;

Fig. 2 is a view of a fragment of the top portion

of the rear of a vest showing the location of the pad in dotted lines;

Fig. 3 is an enlarged sectional view taken on the line 3—3 of Fig. 2;

Fig. 4 is a view similar to Fig. 3 showing a modification in the construction and means of attaching a pad;

Fig. 5 is an enlarged sectional view taken on the line 5—5 of Fig. 8;

Fig. 6 is a perspective view of a pad such as shown in Fig. 3;

Fig. 7 is a perspective view of the pad shown in Fig. 4; and

Fig. 8 is a fragmentary plan view of a portion of the back of a vest with the lining broken away and showing the means of effecting the padding as an integral part of the vest.

In Fig. 1 the numeral 9 designates one of the sides of a vest, which is usually made of a fabric matching the trousers and coat, although there are other types of sport and dress vests made which do not match the trousers and coats, and I wish it to be understood that my invention relates to all types of vests. The parts 9 of the vests, of which there are two to each vest, at their upper ends are usually cut in diagonally, as at 10, from the arm hole and then continue in narrow strips 11 around the back of the neck, there being two parts to the strips 11, one a facing on the inside, and one a neck band on the outside of each part or side 9, joined at the approximate back center of the vest. The outer lining 12 is secured to the upper portion of the vest along the line 10 and covering the lower edges of the neck bands, and the inner lining 13 is secured to the facing. The manner in which the linings 12 and 13 are secured in overlapping relation to the lower edges of the strips 11 is shown in Fig. 3.

In the usual vest there would only be the parts 9, 11, 12 and 13, so that there is no appreciable thickness at the rear of the vest, that is, below the coat collar and between the shoulders, because the facing and lining are usually made of silk, rayon or similar thin material. Consequently the hollow below the neck and between the shoulders is not filled when the coat is put on, with the result that the wrinkle appears on the coat below the collar.

According to my invention, a substantially crescent-shaped pad, designated generally by the numeral 14, Figs. 1 and 2, is provided beneath the strips 11 to lay beneath the collar of the coat and between the shoulders of the wearer, to fill in the hollow between the shoulder blades and to form a smooth surface at the area beneath the

collar and between the shoulders of the wearer to eliminate the wrinkles which usually occur at this point on coats. One of the pads embodying the features of Figs. 1-3 inclusive, is shown in perspective in Fig. 6, comprising two pieces 15 of wadding separated by a piece of hair cloth 16 or other stiffening element, and enclosed by fabric facings 17. The pads can be made in various sizes and thicknesses to suit individual needs, but 10 in actual practice I find that a pad constructed as shown in Fig. 6 is sufficient for general use.

The hair cloth or other stiffening element, of course, is provided to maintain the shape of the pad and may, therefore, have its opposite sides 15 cut concavely as at 18 instead of convexly. This would eliminate the projecting sharp edges of the hair cloth while still stiffening the pad longitudinally and transversely at critical points.

In the pad shown in Fig. 6, the top edges of the 20 fabrics 17, wadding, and hair cloth are all substantially even, but one of the waddings preferably is larger than the other as shown in Fig. 3, to provide a gradual diminishing in the thickness in the pad at its outer edges.

25 In Fig. 3, I have shown the top edges of the pad 14 abutting the lower edges of the neck band and facing forming strip 11, and secured thereto by hand or loop stitches 19. The outer and inner linings 13 overlie the seam formed by the stitches 19, and are secured to the strip 11 by usual stitches 20, so that they enclose and conceal the pad.

In Figs. 4 and 7, I have shown a modification of the invention, wherein the pad designated generally by the numeral 21 is constructed in substantially the same manner as the pad 14, with the exception of the outer fabric coverings which have their upper ends 22 extending above the tops of the wadding and hair cloth. This is to adapt the invention to machine manufacture of clothing 40 by permitting the ends 22 of the fabrics 17 to be inserted between the lower ends of the strips 11, which correspond to the facing and neck band forming strips 11. The linings 12' and 13' overlap the lower ends of the strips 11, and all of the 45 parts, that is, the upper ends of the linings, pad and lower ends of the strips 11 may be united by machine stitching 23. The wadding 15' and hair cloth 16' are separately attached to the facings of the pad.

50 In Figs. 5 and 8, I have shown another form of the invention, wherein the pad instead of being a separate part attached to the vest may be formed integrally therewith. This is accomplished by providing that the strips 11" corresponding to strips 11, instead of being made straight and relatively narrow across the back of the vest, be provided with enlarged portions or curved ends 24 united along the seam 25 to form a substantially crescent-shaped padding, designated generally by the numeral 26, and similar in shape and arrangement to the separate pads of Figs. 1-7. Preferably, a hair cloth piece 27 is inserted between the parts 24, as shown in Fig. 5, and the linings 12" and 13" of the vest are 55 secured in place by stitching 28 which extends also through the parts 24 and the hair cloth 27. Obviously, wadding may be secured between the ends 24 if desired or necessary.

70 It should be apparent from the foregoing, as has been established in actual practice, that a vest made in accordance with my invention presents the same general outward appearance as any other vest, and yet accomplishes "building up the body" to form a smooth and proper foundation for the coat. Furthermore, the outer lin-

ing provides a smooth surface over which the coat may have free movement without catching on the padding, to assume a proper position.

I find that when a vest embodying the features above described is worn beneath a coat which normally wrinkles between the shoulders and below the collar, the wrinkles are eliminated, due to the fact that the built-up portion or increased thickness at the back of the neck in the vest fills out the hollow normally occurring between shoulders. Furthermore, under my invention, the collars of the coats more snugly fit the wearers, even though the wearer may be round-shouldered, whereas, with the pads in the coat the collars tend to stand out or spaced from the neck. 10 15

The above desirable results are accomplished without any visibility or indication that padding is provided beneath the coat, and at the same time the garments may be freely pressed without creating an objectionable shine on the exterior of the coat. 20

I wish it to be understood that the invention may be practiced in connection not only with new garments, but also by inserting the pads or building up the back of the vest in the manner described in old garments. 25

I claim:

1. In a vest having a neck band along the top of its back adapted to overlie the base of the neck of the wearer, a lining on the back of the vest attached at its top to the neck band, and a pad on said vest under said lining concealed thereby at the top of the back of the vest, said pad being of a size and shape such that when the vest is worn the pad occupies an area on the back of the wearer at the base of the neck between the shoulders to fill out the portion of a coat below the collar of the coat and between the shoulder blades of the wearer, and the coat being freely movable with respect to said pad. 30 35 40

2. In a vest having a relatively narrow strip of double thickness extending across the top of the back of the vest, inner and outer linings secured to opposite sides of the strip, and a pad between said linings and having an attaching portion on its top edge in overlapping relation with the parts of said strip and secured thereto, said pad being of a size and shape such that when the vest is worn the pad occupies an area on the back of the wearer at the base of the neck between the shoulders and fills out the portion immediately below the collar of a coat when a coat is worn over the vest. 45 50 55

3. In a vest having portions of the upper ends of the front and facing extending around the back of the vest, the ends of said portions being enlarged at the back of the vest and forming a substantially crescent-shaped padding at the top rear portion of the vest to occupy an area on the back of a wearer at the base of the neck between the shoulders, and said padding being of appreciable thickness and fills out the portion immediately below the collar of a coat when a coat is worn over the vest. 60 65 70

4. In a vest having a neck-band along the top of its back adapted to overlie the base of the neck of the wearer, a lining on the back of the vest attached at its top to the neck-band, and a pad on said vest under said lining concealed thereby at the top of the back of the vest, said pad being of a size and shape such that when the vest is worn the pad occupies an area on the back of the wearer at the base of the neck between the shoulders and fills out the portion immediately below the collar of a coat when a coat 75

is worn over the vest and permitting free movement of a coat when worn over the vest.

5. In a vest having a relatively narrow strip or neck-band extending across the back and forming the top of the back of the vest, a pad secured to the lower portion of said strip in edge to edge relation thereto, and a lining secured to

said strip and covering the pad, said pad when the vest is worn occupying an area on the back of the wearer at the base of the neck between the shoulders and fills out the portion immediately below the collar of a coat when a coat is 5 worn over the vest.
